CLAIM

The ornamental design for a puzzle table as shown and described.

DESCRIPTION

FIG. 1 is a front, top, and left perspective view of a puzzle table showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear, bottom, and right perspective view thereof;

FIG. 9 is a top perspective view of the puzzle table with the top panel in a tilted state;

FIG. 10 is a bottom perspective view of the puzzle table with the top panel in a tilted state; and,

FIG. 11 is a perspective view of the puzzle table with the drawers in an open state.

The broken lines shown in the drawings represent portions of the puzzle table that form no part of the claimed design.

1 Claim, 11 Drawing Sheets
